AXEL JULIUS LARSSON, OF RONNINGE, SWEDEN

STEAM HEATING SYSTEM

Application filed May 25, 1927, Serial No. 194,036, and in Sweden May 29, 1926.

As is well known, in steam heating systems for railway cars radiators connected in parallel as well as in series are used.

The control of the steam quantity supplied to the radiators is generally effected by means of controlling means inserted, at suitable points, in the steam pipe system.

In arrangements having radiators connected in parallel, two pipe lines extending through the cars are commonly used. One of these lines is adapted to supply the required steam to the radiators and the second one to discharge the condensation water formed by the steam condensing in the radiators.

In this case the controlling means is generally placed in front of or within each radiator and the control of the steam supply is effected by throttling, more or less, the passage in said controlling means.

This method of controlling the supply of steam is very objectionable since under certain conditions steam may enter the condensation water line causing the same to wastefully radiate heat at points where it is not desired, and such radiation will take place even though the control means on the radiator for that point is entirely closed. This undesirable radiation may occur at times of minimum steam consumption, at times when the pressure in the main steam line is increased or at times when the steam entering one or more radiators is being throttled.

This entrance of steam into the condensation water line may be properly called a short-circuit, which is undesirable for another reason. For if such a short-circuit occurs through a radiator located near the feed point in the steam line, the steam will be shunted thereby to the condensation water line, and succeeding radiators may not be fed any steam although the control means therefor is at maximum opening. This disadvantage has not been overcome by the use of a central automatic controlling means.

A steam heating system for railway cars has recently been proposed wherein the individual radiators are shunted or in parallel with a steam line which extends through the

cars. In such a system a control means must be placed at the inlet of each radiator to regulate the admission of steam and a control means at the outlet of each radiator to regulate the discharge of the condensed steam. 55 When heat is not desired and the radiator is cut out of the line, there will still be a discharge of the condensed steam from the radiator.

The inconveniences of this last mentioned system are that said outlet for condensation water in cases of cold weather is liable to be choked with ice and that all the condensation water formed in the radiators is forced to pass through the steam line up to and 60 through the last radiator. The result is that at the end of the circuit the steam pipe and radiators will be to a large degree filled with condensation water, which fact prevents the steam from flowing with a sufficient speed. 65 This decreases the efficiency of the heating surface and makes a relatively large heating surface necessary, which fact is very objectionable, especially in movable plants. 70

The above mentioned facts set forth that 75 arrangements for connecting radiators in parallel are particularly inefficient as regards heating as well as controlling.

The present invention relates to a coupling arrangement, by which all the above mentioned inconveniences are avoided, and it is illustrated in the annexed drawing which is a diagrammatic view, partly in section, of an embodiment of a system according to this invention. 85

As shown by the drawing the heating system is divided into two main circuits, a feeding and an equalizing circuit, having a main steam supply pipe 11, 1. The feeding circuit is adapted to supply sufficient steam to the radiators and the equalizing circuit is adapted, in connection with a well known steam controller 2, to control the quantity of steam supplied to said radiators 3. The condensation water formed in the radiators 90 by the condensation of the steam is discharged through a special pipe line 4, 4' into the jacket 17, and is drained therefrom through holes 18 at atmospheric pressure. 95

Said steam regulator 2 comprises a jacket 100

surrounding a thermostatic element 7, said jacket 17 having holes 18 in the bottom thereof through which the condensation water drains. Said thermostatic element 7 actuates a throttle device 6 through a solid rod 19. Said throttle device is placed in the pipe 11 to regulate the flow of steam therein.

Feeders 12 conduct the steam from the main steam supply pipe through valves 8 to the individual radiators 3. The ends of the steam supply pipe 1, which are beyond the points at which the feeders 12 are connected, are joined to an equalizing pipe 5 through valves 9. Said equalizing pipe 5 is connected to jacket 17 by means of a pipe 20 so that any steam entering said equalizing circuit will come in contact with and operate throttling device 6 through the thermostatic element 7 and rod 19.

20 The condensation water is drained from the radiators 3 into jacket 17 through individual outlet lines 14, return mains 4 and 4'.

The arrangement works in the following manner.

25 If the main line 11 is under steam pressure and the throttle device 6 is open, steam will flow through this throttle device into main supply pipe 1 and feeders 12 through the valves 8 into the radiators 3. Any excess steam that does not enter the radiators will pass through the valves 9 to the pressure equalizing line 5. Valves 8 and 9 should be adjusted so that all the steam entering the radiators 3 or equalizing line 5 will be condensed. Therefore with proper adjustment of said valves condensation water only will be discharged through pipe 20 and through outlet lines 14 and pipe lines 4 and 4' to the jacket 17.

40 If the steam pressure in the line 11 should rise or one or more radiators 3 be cut off from steam supply, the steam pressure will increase within the system, which results in the fact that steam, through the pressure equalizing line 5, flows to and acts upon the thermostat 7, which, consequently, acts upon the throttle device 6, so that the steam supply to the radiators 3 and the pressure equalizing line will be lowered till the balance again is established and only condensation water flows through the lines 20, 14, 4 and 4'.

45 The control of the radiation from the different radiators 3 is effected locally by means of the valves 8 and, if desired, centrally by means of a controlling and cutting off device 15 provided with an arrangement 16 for separating the condensation water, said device 15 being located in the steam line 11.

50 The advantage of such a heating system having circuits which are interconnected as described is that no waste results since live steam cannot be discharged with the condensation water for any appreciable length of time. Upon an increase of steam pres-

sure within the feeding circuit, steam may appear in the equalizing circuit, depending of course on the openings in valves 9, if such steam appears it will cause steam controller 2 to throttle the steam in line 11 through the action of thermostatic element 7, rod 19 and throttling device 6. Also valves 8 may be adjusted so that steam will be discharged from outlet lines 14, through the connecting lines 4, 4' into jacket 17, whereupon throttling will again take place in line 11. Consequently outlet lines 14 will not contain steam for any great length of time.

55 Another consideration is that since steam cannot appear in the special pipe line 4 for any appreciable length of time it cannot back up into radiators that are shut off and cause any appreciable heating which is not desired and which is therefore wasteful.

By increased efficiency the heating surface and pipe lines may be reduced, by which fact a considerable saving in construction and working costs is obtained.

Having now particularly described the nature of my invention and the manner of its operation, what I claim is:

A steam heating system for railway cars comprising a steam supply line, a throttling device in said supply line, a discharge pipe, a plurality of radiators inserted in parallel between said supply line and discharge pipe, an individual valve on each radiator, a thermostatic element actuating said throttling device, a jacket encasing the thermostatic element and communicating with the atmosphere, the discharge end of the discharge pipe being connected to said jacket, a second pipe connected to the steam supply line beyond the most remote radiator in the system and also connected to said jacket, and a throttle device in said second pipe.

In testimony whereof I have signed my name to this specification.

AXEL JULIUS LARSSON.
